UNITED STATES PATENT OFFICE.

HIRAM J. ANDRUS, OF AKRON, OHIO.

DESIGN FOR A TIRE.

Application filed October 3, 1921. Serial No. 505,197. Term of patent 3½ years.

To all whom it may concern:

Be it known that I, HIRAM J. ANDRUS, a citizen of the United States, residing at Akron, in the county of Summit and State of Ohio, have invented a new, original, and ornamental Design for Tires, of which the following is a specification, reference being had to the accompanying drawings, forming a part thereof.

Figure 1 is a plan view of a portion of a tire showing my new design.

Figure 2 is a cross sectional view of same taken approximately on the line 2—2 of Figure 1.

I claim—

The ornamental design for a tire substantially as shown.

HIRAM J. ANDRUS.
